UNITED STATES PATENT OFFICE.

FRANK R. HUDSON, OF SAN MATEO, CALIFORNIA.

ARTIFICIAL BUILDING-BLOCK.

No. 921,114.

Specification of Letters Patent. Patented May 11, 1909.

Application filed April 23, 1907, Serial No. 369,850. Renewed December 30, 1908. Serial No. 469,992.

To all whom it may concern:

Be it known that I, FRANK R. HUDSON, a subject of the King of Great Britain, residing at San Mateo, in the county of San Mateo and State of California, have invented certain new and useful Improvements in Artificial Building-Blocks, of which the following is a specification.

The hereinafter described invention relates to an improved artificial building block to be used as a substitute for reinforced concrete in the construction of building walls, the object of the invention being the production of a block which will interlock with adjacent vertically disposed blocks, and be held to adjacent side blocks by a bond joint, the block being reinforced or strengthened by tie rods extended either vertically or longitudinally through bores formed in the block. This object is attained by forming the block with a longitudinally disposed tongue on its upper edge, and a groove or channel in its lower edge, which groove or channel will receive the tongue of an adjacent vertically disposed block, the side edges of the block having therein a vertically disposed groove or channel provided with seats or depressions, which side grooves or channels register with the side grooves or channels of adjacent side blocks to form a filling opening for the reception of liquid cement to bond the blocks laterally, the cement flowing into the filling openings thus formed entering the seats or depressions and forming when the cement has set interlocking keys, and providing the block with a series of vertically extended and a series of longitudinally extended bores through which tie rods are to be passed or extended to reinforce the blocks and hold the same in position.

To comprehend the invention reference should be had to the accompanying sheet of drawings, wherein—

Figure 1 is a perspective view of the improved block; and Fig. 2 is a broken detail view of a series of blocks united.

In the drawings the numeral 1 is used to designate the block, composed of concrete or other suitable material, which block is provided on its upper edge with a projecting longitudinally disposed tongue 2. In the bottom edge of the block is formed a longitudinally extended groove 3, the purpose of which groove in the bottom edge of the

block and the tongue on the upper edge of the block is that when the blocks are placed in the wall construction, the tongue of one block will interlock with the groove of an adjacent vertically disposed block.

In each side edge of the block is formed a vertically disposed groove 4, in which grooves a series of rectangular shaped depressions or seats 5 are provided. These grooves register with corresponding grooves of adjacent side blocks when positioned in the wall and form a filling space for the reception of liquid cement poured therein to form a bond for the blocks. The cement thus poured into the filling space enters and fills the seats or depressions 5 and forms, when the cement has set, a series of inwardly extended tongues, to give a stronger union between the blocks. The longitudinally disposed tongue 2 of the block is provided with rectangular shaped seats or depressions 10 and similar seats or depressions 11 are provided in the groove 3 of the bottom edge of the block. These seats 10 and 11 are adapted to receive cement to assist in bonding the blocks. Each block is formed with a series of vertically disposed bores 6 arranged alternately with respect to the seats or depressions 10 and 11, and a series of longitudinally disposed bores 7 arranged alternately with respect to the seats or depressions 5, which bores are for the reception of a series of tie rods 8 during the wall construction. These rods serve to reinforce the wall as constructed, and to tie the blocks together and to hold the same in position within the wall.

The expense of constructing a reinforced wall by the use of the described blocks is considerably less than by the employment of reinforced concrete, and the wall may be formed more rapidly.

Having thus described the invention what is claimed as new and desired to be protected by Letters Patent is—

A block for the construction of reinforced walls, the same being formed on its upper edge with a projecting longitudinally disposed tongue and on its lower edge with a longitudinally disposed groove, the side edges having a vertical groove therein, the grooves of the side and bottom edges of the block and the projecting longitudinally disposed tongue thereof being provided with spaced rectangular shaped depressions, said

block being provided with a series of vertically disposed bores therethrough and a series of longitudinally disposed bores therethrough for the reception of tie rods, the longitudinal bores being arranged alternately with the rectangular shaped depressions of the grooves in the side edges.

In testimony whereof I have signed my name to this specification in the presence of two subscribing witnesses.

FRANK R. HUDSON.
